UNITED STATES PATENT OFFICE.

WINTWORTH V. LANDER, OF NEWTON, MASSACHUSETTS, ASSIGNOR TO GENERAL INDURATING CORPORATION, OF NEW YORK, N. Y., A CORPORATION OF NEW YORK.

IMPREGNATING APPARATUS.

1,339,400.

Specification of Letters Patent. Patented May 11, 1920.

Original application filed December 20, 1916, Serial No. 137,959. Patent No. 1,277,322. Divided and this application filed July 31, 1918. Serial No. 247,662.

To all whom it may concern:

Be it known that I, WINTWORTH V. LANDER, citizen of the United States of America, and resident of Newton, in the county of 5 Middlesex and State of Massachusetts, have invented new and useful Improvements in Impregnating Apparatus, of which the following is a specification.

This invention relates to apparatus for 10 filling or impregnating bodies characterized by porous or interstitial structure and which are therefore bibulous, the present application being a division of my prior application Sr. No. 137,959, filed December 20, 1916 15 (Pat. No. 1,277,322, granted Aug. 27, 1918.)

The bodies or substances which are susceptible of treatment by my new apparatus are exemplified by compressed wood-pulp articles, such as pulp-boards, pails, toilet-seats, etc., and also flexible sheet materials such as paper, textiles, paper board, leather board, and leather, all of which are characterized by interstitial structure and capable of taking up a liquid by capillary absorption. The present apparatus may be employed to impregnate these and other articles either superficially or through and through.

A primary object of my invention is to 30 render porous or bibulous bodies impervious or resistant to water by reason of the increased or enhanced internal structural continuity imparted to such bodies by my improved mode of impregnation. Other objects are either to indurate and toughen porous bodies such as wood-pulp articles or to toughen and render pliable materials such as leather and textiles depending upon the proportions of ingredients used in the impregnating composition; and in the case of leather particularly to fill, plump, refine the grain, increase the tensile strength, and generally to improve the physical characteristics of leather so as to raise its grade and market 45 value. Another object is to deposit the impregnating substance in the body of the material without leaving much if any of the substance deposited upon the external surface of the material.

Still further objects of the invention will 50 be apparent from the following description and the accompanying drawings, in which,—

Figure 1 is a vertical transverse section of the preferred embodiment of my improved apparatus;

55

Fig. 2 is a top plan view of the apparatus; and

Fig. 3 is a vertical longitudinal section of the apparatus.

The impregnating composition which I 60 preferably employ in my improved apparatus comprises crude petrolatum and rosin dissolved in gasoline, although it will of course be understood that the apparatus may be employed with any suitable composition. 65 When using crude petrolatum and common rosin dissolved in gasoline, the gasoline serves as a volatile carrier to carry the mixture of petrolatum and rosin into the material to be impregnated and is then removed 70 by evaporation. By increasing the proportion of rosin the treated materials may be hardened and stiffened and by increasing the proportion of petrolatum the treated materials may be rendered more soft and pliable. 75 The composition is preferably applied by dipping the materials or articles into the composition and my improved apparatus is particularly intended for this purpose.

In the accompanying drawings, A represents a tank, (which may be of galvanized iron) about two feet wide, five feet high, and as long as the nature of the work requires. Heating pipes D, for steam or other heating agent, lie at the bottom of the tank A, and 85 a perforated or wire-mesh screen is placed over these pipes, to prevent a skin or other article from touching the hot pipes. C is an inclined apron having a number of large perforations C' to facilitate circulation of 90 fluid. This apron is provided for the purpose of preventing a skin from falling and crumpling on itself at the bottom of the tank, when introduced for treatment. Near the top of the tank A and adjacent to the 95 sides thereof there is a coil of pipe E, through which a cooling fluid is circulated so as to supplement the cooling and condensing effect of the upper parts of the walls of the tank A. By prolonging the walls of the 100 tank upward, the cooling and condensing effect can be obtained without the employment of cooling pipes or other refrigerating or condensing devices. Roll-shafts F and F'

at the top and bottom of the tank A, respectively, carry conveyer chains or belts G which are provided with cross-rods H, on which clips or other convenient attaching devices are secured. The pulley J (Figs. 2 and 3) driven from any suitable source of power, rotates shaft F and thus causes the conveyer to move in the tank A.

- The tank being filled to the level L, L', (say nine inches to a foot above the false bottom or grating B) with the crude petrodatum-rosin-gasolene composition, steam is circulated through the pipes D, causing the composition to boil. The vapor generated rises in the tank, is condensed and falls back either as a mist or as liquid which trickles down the sides of the tank. Immediately above the liquid composition there is maintained an atmosphere of gasolene vapor. The effect of the condensation is to keep gasolene vapors from escaping into the room, in which, although gasolene is being boiled in an open vessel, there will be hardly a noticeable gasolene odor.
- 25 A skin, as for instance a sheep or calf-skin, coltskin, cowhide, or any kind of skin or hide, is attached to clips H and carried down into the tank A. The operator holds the free end of the skin S until it may be lowered down upon the inclined apron C, where the leather clings slightly on account of the wetness of the surface of the apron, and is drawn through the boiling composition and lifted out, as the conveyer G travels. As the hide or skin enters the composition the air is driven out of the pores and the composition solution strikes in, thoroughly impregnating the leather. As the leather is drawn out of the composition it is bathed in the vapor which occupies the central part of the tank, over the liquid level, and this vapor-washing removes from the surface of the leather all streaks of greasy material which otherwise might remain and degrade the leather. This vapor bath degreases the leather to a slight degree, just enough to clean its surface thoroughly. The leather is then hung up to dry, either in the open, or in a drying room.
- 50 The physical character of the product depends on the selection of proportions of ingredients in the treating composition, and almost any desired variation in result can be obtained after experience with, and manipulation of, the composition. For instance, to make an improved waterproof leather, use equal parts of crude petrodatum and rosin, and an amount of gasolene which weighs about eighty per cent of the combined weight of the other two ingredients. If the gasolene is of specific gravity sixty, heat it to 200° F. in the treating tank and regulate the travel of the conveyer so that the leather will be immersed about fifteen 65 seconds. The product, after drying, will be

firmer, harder, and less flexible than the untreated leather, will be permanently waterproof, much more resistant to wear, and has a surface susceptible of receiving a high polish.

If a leather for gloves or light shoe upper is to be produced, say from calfskin, use to each gallon of gasolene two pounds of rosin and three pounds of crude petrodatum, and treat the leather with this composition as 70 hot as 200° F. or hotter. The leather usually need not be immersed longer than ten seconds. The product is well plumped, the quality and feel of the grain refined and improved; the leather is soft and flexible, 75 of higher tensile strength than originally, and improved in grade. It is, like all products thus treated with my composition, 80 completely waterproof. This treatment does not seem to affect coloring matter in the 85 leather, but imparts improved character to all kinds of leather without incidental detriment. Cemented laminated leather belting can be advantageously treated with my composition which imparts the waterproof character to the belting, increases its tensile strength, decreases its liability to stretching, and gives it a traction surface which requires little or no belt-dressing.

The vapor bath given to leather on emerging from the liquid composition in apparatus such as above described is particularly important and beneficial, since it prevents any greasy streaks or exudations from remaining on the surface of the leather.

As to treatment of other flexible materials than leather; I have waterproofed cloth garments, tent cloth and miscellaneous textile articles, by giving them a single treatment in all essentials like that above prescribed for flexible glove or upper leather. I have also treated wood-pulp articles, using a composition of four pounds of rosin and three pounds of crude petrodatum to the gallon of gasolene, immersing the wood-pulp 10 articles in the composition at a temperature about 200° F., leaving them immersed long enough to insure thorough penetration. The product when dry is highly indurated, 11 tough, and takes a high polish. The complete waterproof character of the product adapts such impregnated wood-pulp to a variety of uses. The articles of wood-pulp will be molded to their desired and intended shape before impregnation.

As a general rule, the high grades of gasolene—such as commercial 70 to 75 specific gravity gasolene—form a composition which need not be heated to so high a point for good results in treatment of porous bodies. 12 With such gasolene, the temperature need not be much above 150° F.

The time of immersion of a body to be impregnated will depend on the degree of penetration or impregnation desired, the 13

thickness of the body, the degree of fineness of its pores or interstices, the temperature of the composition, and the degree of concentration of soluble ingredients therein.

5 By variations in these factors almost any conceivable character or degree of impregnation can be obtained.

I claim:

1. Apparatus for impregnating articles in a volatile solution comprising an open tank adapted to contain the volatile solution at the bottom and to confine vapor from the solution above the solution, the tank being relatively narrow and deep so that the vapor rising to the upper portion thereof is condensed when the tank is surrounded by a relatively cold medium whereby the vapor is restrained from escaping from the tank, and means for passing articles through the solution and then through the vapor.

2. Apparatus for treating materials with solutions in volatile solvent, comprising a vessel having an opening for the introduction of materials to be treated, and means to condense vaporized solvent emanated by a solution in the vessel, the condensing means being disposed between the solution and said opening.

3. Apparatus for treating materials with solutions in volatile solvent, comprising a vessel open for the introduction of materials to be treated, means to heat a solution in the vessel, and means at an upper part of the vessel to condense vaporized solvent emanated by a solution in a lower part of the vessel.

4. Apparatus for treating materials with solutions in volatile solvent, comprising a vessel open for the introduction of materials to be treated, means to heat a solution in the vessel, and refrigerating means at an upper part of the vessel to condense vaporized solvent emanated by a solution in a lower part of the vessel.

45 5. Apparatus for treating materials with solutions in volatile solvent, comprising a vessel open for the introduction of materials to be treated, means to heat a solution in the vessel, a perforate shield over the heating means, and means at an upper part of the vessel to condense vaporized solvent emanat-

ing from a solution in a lower part of the vessel.

6. Apparatus for treating materials with solutions in volatile solvent, comprising a vessel open for the introduction of materials to be treated, a conveyer to carry materials into and out of a solution in the vessel, and means at an upper part of the vessel to condense vaporized solvent emanated by a solution in a lower part of the vessel.

7. Apparatus for treating materials with solutions in volatile solvent, comprising a vessel open for the introduction of materials to be treated, a conveyer to carry materials into and out of a solution in the vessel, means to heat a solution in the vessel, and means at an upper part of the vessel to condense vaporized solvent emanated by a solution in a lower part of the vessel.

8. Apparatus for treating materials with solutions in volatile solvent, comprising a vessel open for the introduction of materials to be treated, a conveyer to carry materials into and out of a solution in the vessel, and refrigerating means at an upper part of the vessel to condense vaporized solvent emanated by a solution in a lower part of the vessel.

9. Apparatus for treating materials with solutions in volatile solvent, comprising a vessel open for the introduction of materials to be treated, a conveyer to carry materials into and out of a solution in the vessel, means to heat a solution in the vessel, a perforate shield over the heating means, and means at an upper part of the vessel to condense vaporized solvent emanating from a solution in a lower part of the vessel.

10. Apparatus for treating materials with solutions in volatile solvent, comprising a vessel open for the introduction of materials to be treated, a conveyer to carry materials into and out of a solution in the vessel, an apron in the vessel to support materials while in conveyance through the vessel, and means at an upper part of the vessel to condense vaporized solvent emanated by a solution in a lower part of the vessel.

Signed by me at Boston, Massachusetts, this 25th day of April, 1918.

WINTWORTH V. LANDER.
